DESIGN FOR A COMBINED WALL SHELF, MIRROR, AND TOWEL BAR

Ellis M. Johnson, Chicago, Ill.

Application August 21, 1945, Serial No. 121,553

Term of patent 14 years

(Cl. D33—3)

To all whom it may concern:

Be it known that I, Ellis M. Johnson, a citizen of the United States of America, residing at 4911 N. Hermitage Ave., Chicago, in the county of Cook and State of Illinois, have invented a new, original, and ornamental Design for Combined Wall Shelf, Mirror and Towel Bar, of which the following is a specification, reference being had to the accompanying drawing, forming part thereof.

I claim:

The ornamental design for a combined wall shelf, mirror, and towel bar, substantially as shown.

ELLIS M. JOHNSON.
